CLAIM

The ornamental design for a data storage device, as shown and described.

DESCRIPTION

FIG. 1 is a top, front and side perspective view of a data storage device showing the new design;
FIG. 2 is a bottom, back and side perspective view thereof;
FIG. 3 is a front view thereof;
FIG. 4 is a back view thereof;
FIG. 5 is a first side view thereof;
FIG. 6 is a second side view thereof;
FIG. 7 is a top view thereof; and,
FIG. 8 is a bottom view thereof.

The regular dash-dot broken lines show unclaimed features of the storage device and form no part of the claimed design. The pairs of wavy adjacent broken lines running through the center of the device form no part of the claimed design and the portions between such lines that may be visible have been removed for clarity. The diagonal broken line hatching
